HAIR TREATING MACHINE

Bertha A. Dodd, Washington, D. C.

Application February 21, 1944, Serial No. 523,355

5 Claims. (Cl. 132—31)

1

The primary object of my invention is to provide a machine for the removal of kinks and curls in human hair.

My invention consists of a machine having means to put the hair under tension and hold it thus for a predetermined time in the presence of heat and a suitable liquid; and consists further in the parts and combination of parts hereinafter specified.

Figure 1 is a top plan view of my improved machine.

Figure 2 is a side elevation of Figure 1.

Figure 3 is a sectional view on the line 3—3, Figure 1.

Figure 4 is a longitudinal sectional view on the line 4—4 of Figure 1.

Figure 5 is a transverse sectional view on the line 5—5 of Figure 1.

Figure 6 is a transverse sectional view looking towards the hair clamp, the clamp being open for the reception of hair.

Figure 7 is a top plan view of the hair tension roll, detached from the machine.

Figure 8 is a side elevation of Figure 7, the clamping jaw being open.

Figure 9 is a detail sectional view of one end of the winding roll.

The reference numerals 1 and 2 designate the side bars of the frame of my machine. To one end of the bar 1 is secured an angle iron 3 and to one end of the bar 2 is secured an extension 4. The lower hair clamping roll, or member, 5 is rigidly secured to the angle iron 3 and extension 4, as clearly shown in Figures 1 and 6. The upper hair clamping roll or member 6 is pivotally secured at one end between arms 7 extending upwardly from the extension 4 and is provided with an arm 8 extending axially from its free end, said arm being provided with a cam recess 9.

Pivoted between the upper ends of the arms 7 on the angle irons 3 is the hair clamp locking lever 10 having a cam 11 extending at right angles to the lever and designed to engage the cam recess 9 of the upper hair clamping member to firmly hold the said members in the locked position shown in Figure 2.

As illustrated in Figures 2 and 3, the side bars of the machine are provided with notches of different shape; the notches 12 on bar 1 having a rounded bottom seat 13, while the notches 14 in bar 2 are provided with a flat seat 15, the purpose of which will hereinafter be described.

The hair tension roller 16 is provided with a clamping lever 16' pivoted near one end of the member, as clearly shown in Figure 8, and is con-

2

caved to coact with the perimeter of the member 16. The member is provided with a round rod-like extension 17, at each end of which is a collar 18, an operating handle 19 extending from the tension member beyond the outermost collar 18. The opposite end of the hair tensioning member 16 is provided with a socket 20 in which is positioned a clutch member 21 having an extension 22 of reduced diameter provided at its free end with a slot 23; a coiled spring 24 surrounds the reduced portion 22 one end of which is anchored in the slot 23 while its other end is seated on the base of the plunger, as shown in Figure 9. The outer end 24a of the member 22 extends beyond the end of the tension member 16 and terminates in a right angle arm 25, rectangular in cross section.

This hair tension member is positioned between the side bars 1 and 2, with the round rod portion 17 resting on the curved seat 13 of the notch 12 in bar 1, while the rectangular extension 24a is seated on the flat seat 15 of the bar 2, the right angle portion 25 bearing against the outer face of the bar 2 adjacent the notch 17. The hair tension member may be revolved on the rod 17 and member 21; the extension being rectangular and fitting in the seat of the notch 14 is held against revolution. The free end of the spring 24 has sufficient frictional contact with the wall of the recess 20 to hold the hair tension roll in the desired position to hold the hair under the desired tension for the desired period of time.

The machine is further provided with a casing comprising the top and bottom covers 26 and 26', respectively. These covers are each provided with (preferably) an electric heating coil 27 surrounded by suitable insulation 28. The coils are coupled with a source of supply 29.

40 The covers 26, 26' are fixed at one end to the inner ends of operating handles or members 30 which are centrally pivoted together by means of a transverse pintle pin 30' and provided at their outer ends with operating knobs 30a. A coiled spring 30b has its coiled portion encompassing the pivot pin 30' and has its ends arranged to bear upon the handles outwardly beyond the pivot point 30' so as to normally exert pressure to spread the outer ends of the handles apart and 45 to move the cover 26, 26' towards each other or into clamping position. The cover members are thus pivotally united to form an openable and closable cover in which said cover members are normally moved toward each other to close the cover, and in which said cover members are

adapted to be swung apart to open the cover by pressure on the knobs 30a whereby the cover members may be moved apart against the resistance of the spring 30b. When the cover members are spread apart or opened the cover may be applied for use or removed by sliding it inwardly or outwardly longitudinally of the frame, over the tensioning member 16. The cover when applied obviously acts as a spring clamp to clamp the pads 31 against the gripped strand of hair. Preferably the inner ends of the frames of the handles 30' are recessed, as shown at 30c, and the adjacent ends of the cover members 26, 26' are recessed, as shown at 30d, to adapt them to close about the tensioning device 16 and clamp 16' when the cover is applied and disposed in clamping position against the pads 31. The arrangement of the sets of recesses is such, as shown in Fig. 4, that when the cover is applied the recessed portions 30d respectively overlie and underlie the tensioning device 16 and clamp 16' and adapt the cover members to straddle the same to lock the clamp 16' against casual opening movement, while also adapting the cover members to be swung to open and closed positions on the pivot 30' without interference from the tensioning device 16 or clamp 16'.

After the hair A has been placed under the desired tension, pads 31 saturated with the desired solution are placed over the hair and the covers closed.

In practice the clamping members 5 and 6 are positioned on the head as close to the scalp as deemed necessary and the hair A to be straightened is placed between the clamping members and the member 6 is then swung onto the hair and locked in position by the locking lever 10. The free ends of the hair are then given a preliminary turn around the tension roller 16 until there is a fairly tight tension placed on the hair, when the clamping bar 16' is then moved in the position shown in Figure 7, whereupon the hair is firmly held on the tension roll. The tension roller or member is then revolved until the necessary tension is placed on the hair to straighten out the kinks or curls, whereupon the pads 30 are placed over the hair and the hinged covers closed over the pads and hair. These pads may be saturated with any desired solution.

After the hair has been under the necessary tension and held in that condition the desired time, the covers are then raised off of the pad and hair, the pads removed and the hair is then washed in any suitable manner to remove the solution. The time of treatment may be controlled with any suitable means to cut off the electric current, but this feature is not claimed and hence not illustrated.

The series of notches in the side bars of the frame enable me to position the tensioning member relatively to the clamping member to take care of hairs of different lengths.

What I claim is:

1. In a hair straightening device, the combination of a frame, a clamp supported on the frame at or near one end of the frame for clamping a strand of hair near its roots, a tensioning device supported on the frame at or near the opposite end of the frame and in spaced relation to the clamp for gripping and tensioning the free end of a strand extended thereto from the clamp, and a heater comprising a pair of pivotally connected handles adapted to be disposed at the second-named end of the frame in juxtaposition to the tensioning device and a pair of cover members

having heating means therein and attached at one end to the handles so as to be movable thereby by pivotal movements thereof to open and closed positions and whereby said cover members are adapted to be passed in open position over the tensioning device and disposed between the clamp and tensioning device and brought to lie in closed position with their inner faces in proximate relationship on opposite sides of the clamped strand, the inner surfaces of the ends of said cover member attached to the handles being recessed to receive and partially enclose the tensioning device to allow the cover members to swing to open and closed positions without interference from the tensioning device and to allow said faces of the cover members in their closed position to come into close heating relation to the clamped strand.

2. In a hair straightening device, the combination of a frame, a clamp supported on the frame at or near one end of the frame for clamping a strand of hair near its roots, a tensioning device supported on the frame at or near the opposite end of the frame and in spaced relation to the clamp for gripping and tensioning the free end of a strand extended thereto from the clamp, and a heater comprising a pair of pivotally connected handles adapted to be disposed at the second-named end of the frame in juxtaposition to the tensioning device, a pair of cover members having heating means therein and attached at one end to the handles so as to be movable thereby by pivotal movements thereof to open and closed positions and whereby said cover members are adapted to be passed in open position over the tensioning device and disposed between the clamp and tensioning device and brought to lie in closed position with their inner faces in proximate relationship to opposite sides of the clamped strand, and spring means acting on the handles to normally hold the handles and cover members closed, the inner surfaces of the ends of said cover members attached to the handles being recessed to receive and partially enclose the tensioning device to allow the cover members to swing to open and closed positions without interference from the tensioning device and allow said faces of the cover members in their closed position to come in close heating relationship to the clamped strand.

3. In a hair straightening device, the combination of a frame having side members, a clamp supported on the frame members at or near one end of the frame for clamping a strand of hair near its roots, a tensioning device supported on the frame members at or near the opposite end of the frame and in spaced relation to the clamp for gripping and tensioning the free end of a strand extended thereto from the clamp, said tensioning device including a part rotatably engaging one of the side members of the frame, a clamp for holding the strand in engagement with the rotatable part, a non-rotatable part engaging the other side of the frame and resilient means coupling said parts and adapted to permit rotation of the first mentioned part to tension the strand and to act thereon to hold the strand under elastic tension, and a heater comprising a pair of pivotally connected handles adapted to be disposed at the second-named end of the frame in juxtaposition to the tensioning device and a pair of cover members having heating means therein and attached at one end to the handles so as to be movable thereby by pivotal movements thereof to open and closed positions, said cover members adapted to be passed in open

position over the tensioning device and disposed between the clamp and tensioning device and brought to lie in closed position with their inner faces in proximate relationship to opposite sides of the clamped strand, the inner surfaces of the ends of said cover members attached to the handles being recessed to receive and partially enclose the tensioning device to allow the cover members to swing to open and closed positions without interference from the tensioning device and to allow said faces of the cover members in their closed position to come into close heating relationship to the clamped strand.

4. In a hair straightening device, the combination of a frame having side members, a clamp supported on the frame members at or near one end of the frame for clamping a strand of hair near its roots, a tensioning device supported on the frame members at or near the opposite ends of the frame and in spaced relation to the clamp for gripping and tensioning the free end of a strand extended thereto from the clamp, said tensioning device including a part rotatably engaging one of the side members of the frame, a clamp for holding the strand in engagement with the rotatable part, a non-rotatable part engaging the other side of the frame and resilient means coupling said parts and adapted to permit rotation of the first named part to tension the strand and to act thereon to hold the strand under elastic tension, and a heater comprising a pair of pivotally connected handles adapted to be disposed at the second-named end of the frame in juxtaposition to the tensioning device, a pair of cover members having heating means therein and attached at one end to the handles so as to be movable thereby by pivotal movement thereof to open and closed positions and whereby said cover members are

adapted to be passed in open position over the tensioning device and disposed between the clamp and tensioning device and brought to lie in closed position with their inner faces in proximate relationship to opposite sides of the clamped strands, and spring means acting on the handles to normally hold the handles and cover members closed, the inner surfaces of the ends of said cover members attached to the handles being recessed to receive and partially enclose the tensioning device to allow the cover members to swing to open and closed positions without interference from the tensioning device and to allow said faces of the cover members in their closed position to come into close heating relationship to the clamped strand.

5. In a hair straightening device, a clamp to engage a strand of hair adjacent to the scalp, a tensioning device to engage the free end of the strand and hold the strand under tension, means for supporting said clamp and strand in spaced relation, and a removable heater comprising a pair of internally heated heating members having pivotally connected actuating handles at one end thereof coupling them jaw-fashion for opening and closing movements to adapt said members to be passed for application and removal over the tensioning device and to be disposed when applied on opposite sides of the tensioned strand and moved toward and from the same into and out of heating position relative thereto to lie lengthwise of the heater on opposite sides of the tensioning device and having portions formed to straddle and partially enclose said device in spaced relation thereto to allow the heating members to freely swing without interference from the tensioning device into and out of heating position.
